UNITED STATES PATENT OFFICE.

WILLIAM TREVENA WILLIAMS IDRIS, OF CAMDEN TOWN, LONDON, AND WILLIAM OLIVER ROSS, OF HORNSEY, ENGLAND, ASSIGNORS TO IDRIS & CO., LIMITED, OF LONDON, ENGLAND.

SIPHON FOR AERATED LIQUIDS.

1,099,850.

Specification of Letters Patent.

Patented June 9, 1914.

Application filed May 22, 1913. Serial No. 769,181.

To all whom it may concern:

Be it known that we, WILLIAM TREVENA WILLIAMS IDRIS and WILLIAM OLIVER ROSS, subjects of the King of Great Britain, residing, respectively, at 244 Camden road, Camden Town, in the county of London, England, and 1 Hillfield avenue, Hornsey, in the county of Middlesex, England, have invented new and useful Improvements in Siphons for Aerated Liquids, of which the following is a specification.

This invention relates to siphons in which the nozzle and valve seat are formed in a single block generally of porcelain or the like, and particularly to siphons of the kind shown in U. S. Patent No. 1,049,364 of January 7, 1913, granted to W. T. W. Idris, in which the porcelain block is put into place sidewise through a side opening in the casing of the siphon top and is secured in place after it has been thus positioned by means of a collar screwing into the casing and pressing against the under side of the block.

In the patented siphon above referred to, friction alone was relied upon for preventing the block from moving sidewise out of the side opening in the casing. According to the present invention the collar is made to engage a shoulder or similar device on the under side of the block and to thus prevent the block from moving sidewise out of the opening. We also provide the block with a shoulder to fit the side opening in the casing and thus prevent rotation of the block.

Figure 1 is a side elevation and Fig. 2 is a vertical section of a "short lever" siphon top constructed according to this invention. Fig. 3 is a plan, Fig. 4 a side elevation and Fig. 5 an underside view of the block. Fig. 6 is a vertical section of a modification.

a is the vase having the usual split ring *b* around its neck and *c* is the descending tube.

d is the casing made in one piece of metal and screwing on to the split ring *b*.

e is a cap screwing onto the top of the casing *d*.

f is a porcelain block provided with a nozzle *g* and having in its underside a segmental groove *h* concentric with the valve seat *i*.

j is a collar screwing into the casing *d* and engaging with the groove *h*.

k is a washer interposed between the vase *a* and the block *f*.

l is the valve carried by the spindle *m* and operated by the lever *n* pivoted at *o* and 55 working against the spring *p* the lower end of which bears on the washer *q* surrounding the spindle *m*.

It will be observed that the groove *h* provides a shoulder *h'* against which the 60 collar *j* bears and thus prevents the block from being removed from the casing until the collar is disengaged. We prefer to use a segmental groove to receive the collar but any kind of a projection or shoulder may 65 be employed for this purpose. The opening in the casing *d* is just sufficient in size to admit the block, the lower face of which is on the same plane with the lower wall of the opening. The collar *j* when screwed 70 home, however, projects above the plane of the lower wall of the opening and the lower face of the block, engages the shoulder *h'* and prevents the withdrawal of the block.

In assembling the parts the washer *q* is 75 first put into its recess in the top of the block *f* and the latter is put sidewise into the casing through the side slot or opening in it. The collar *j* is then screwed up in the casing until it engages with the groove *h* 80 and firmly holds the block in place. The valve stem *m* surrounded by its spring *p* is next dropped in at the top of the casing and the stem is passed through the washer *q* and the valve *l* is screwed onto it. Lastly the 85 lever *n* and cap *e* are put into place and the whole is screwed onto the split ring *b*. The block *f* is provided with shoulders *f'* on opposite sides of the nozzle *g* and these shoulders fit the casing on opposite sides 90 of the side opening therein and prevent the rotation of the block.

Fig. 6 is a vertical section showing the application of the invention to a "long lever" siphon top. *a* is the vase, *b* the split 95 ring and *c* the descending tube. *d* is the tubular casing screwing onto the split ring and *e* is the cap screwing onto the casing. *f* is the porcelain block and *g* is the nozzle having on its under side a segmental groove 100 as before. *j* is a collar screwing into the casing *d* and engaging with the groove. *k*

is a washer interposed between the vase *a* and the block *f*. *l* is the valve carried by the spindle *m* and operated by the lever *n* pivoted at *o* and working against the 5 spring *p*.

What we claim is:—

1. In a siphon head, the combination of a casing having an opening at one side, a block within the casing and which is insertible and removable through the side opening and is provided on its under-side with a shoulder, a nozzle fixed to the block and projecting through said opening, and a collar screwing into the casing extending above the plane of the lower wall of the side opening and the lower face of the block within the casing and engaging said shoulder to prevent sidewise withdrawal of the block through said opening.
- 10 2. In a siphon head, the combination of

a casing having an opening at one side, a block within the casing which is insertible and withdrawable through said side opening and which has a shoulder engaging said casing at the side of said opening to prevent the rotation of the block, and another shoulder on its under-side, a nozzle fixed to the block and projecting through said opening, and a collar screwing into the casing extending above the plane of the 25 lower wall of the side opening and above the plane of the lower face of the block and which engages said shoulder on the under-side of the block and prevents sidewise movement thereof.

WILLIAM TREVENA WILLIAMS IDRIS.

WILLIAM OLIVER ROSS.
